UNITED STATES PATENT OFFICE.

EDWARD POSSON, OF CHICAGO, ILLINOIS.

COMPOUND BRAKE MECHANISM.

1,399,078.

Specification of Letters Patent.

Patented Dec. 6, 1921.

Application filed February 27, 1920. Serial No. 361,645.

To all whom it may concern:

Be it known that I, EDWARD POSSON, a citizen of the United States, residing at Chicago, in the county of Cook and State of Illinois, have invented certain new and useful Improvements in Compound Brake Mechanism, of which the following is a specification.

This invention relates to compound brake mechanism for railway cars and its purpose is to provide means which is capable of use with the usual brake mechanism heretofore used for multiplying the power transmitted through the brake mast or shaft. The principal object is to provide a housing containing multiplying gears which may be applied to the lower end of the usual vertical brake mast without altering any of the parts of the usual car construction. Other objects relate to various features of construction and arrangement which will appear more fully hereinafter.

The nature of the invention will be understood from the following specification taken with the accompanying drawings in which one embodiment is illustrated.

In the drawings—

Figure 1 shows a top plan view of the end sill of the car with my improved brake mechanism applied thereto;

Fig. 2 shows an end elevation of the end sill and brake mechanism;

Fig. 3 shows a vertical section on the line 3—3 of Fig. 2;

Fig. 4 shows a horizontal sectional view on the line 4—4 of Fig. 3; and

Fig. 5 shows a perspective view of the housing in which the gears and counter shaft are mounted.

The invention is shown applied to brake mechanism located at the end of a railway car which comprises an end sill made up of a transverse channel beam 10 and an upper horizontal plate 11. The usual longitudinal sills 12 extend longitudinally from the transverse beam 10. The usual step 13 is located at the end of the car beneath the end sill, this step comprising the lower horizontal portion 13^a adapted to be engaged by the foot of the brakeman or other trainman. The upper arms of the step are twisted, as shown at 13^b, so that the upper ends thereof lie parallel to the channel beam 10 to which they are secured by rivets 14. A vertical brake mast or shaft 15 extends upwardly at the end of the car on the outer side of the

end sill and the lower end of this brake mast is provided with a part 15^a which is reduced in diameter and journaled in a bearing which is formed in the lower horizontal portion 13^a of the step 13, this part of the step being offset outwardly from the end sill, as shown in Fig. 3. The brake mast extends upwardly in close proximity to the edge of the plate 11 and is journaled loosely in a bearing 16 which is formed as a part of a bracket 17 secured by rivets 18 on the upper surface of the plate 11. A ratchet wheel 20 is secured to the brake mast 15 above the bearing 16 by means of a key 21 and this ratchet wheel is adapted to be engaged by a pawl 22 which is pivoted on the bracket 17 by means of a bolt 23. The pawl 22 has an arm 22^a adapted to be engaged by the foot of the brakeman when it is desired to release the ratchet wheel and permit the rotation of the brake mast. It will be understood that the brake mast extends upwardly and is provided on the upper part thereof with a hand wheel or other usual means for rotating it.

The brake mast is provided adjacent its lower end above the step 13^a with an enlarged portion 15^b which ordinarily serves as a drum upon which the brake chain is wound. The present invention contemplates the removal of the brake chain from the drum 15^b and the substitution at the lower end of the brake mast of multiplying gears by which the power applied to the brake chain is increased at the expense of an increased relative rotation of the brake mast. This improvement comprises a housing 25 which embodies a vertically extending bearing portion 25^a journaled on the part 15^a of the mast and formed integrally with the upper and lower arms 25^b and 25^c, respectively. The upper and lower arms of the housing are reinforced on their inner sides by a rib 26 and the lower arm of the housing comprises upper and lower walls 27 and 28, respectively, which are spaced apart and partially or wholly inclosed to form an intervening chamber 29. The lower wall 28 is provided with an aperture 30 adapted to be rotatably engaged by the reduced portion 15^a of the brake mast, and the portion of the drum 15^b immediately above the part 15^a is cut down to form a part 31 of rectangular cross section adapted to be engaged by a pinion 32 located in the chamber 29. This pinion meshes with a larger gear 33 which is also mounted between the walls 27 and 28.

and which is engaged by a rectangular part 35^a of a counter shaft or drum 35. This drum is journaled in the upper arm 25^b and in the upper wall 27 of the lower arm 25.
 5 The lower extremity of this counter shaft is reduced in diameter, as shown at 35^b, and this portion is journaled in the lower wall 28 of the lower arm of the housing. Vertical movement of the counter shaft and of the
 10 brake mast 15 is prevented by means of pins 37 extending through the apertures which are formed in the lower extremities of these shafts. That portion of the drum 35 which lies between the upper and lower arms of the
 15 housing 25 is adapted to effect the winding of the brake chain 38 which is secured thereto by means of a transverse bolt 39.
 Upon rotation of the brake mast 15, the pinion 32 at the lower end thereof drives the
 20 larger gear 33 and effects the winding of the chain 38 upon the drum 35. The housing 25 is adapted to swing freely on the mast 15 but it ordinarily assumes the position illustrated in Fig. 3 by reason of the pull exerted
 25 by the chain 38. It will be observed that the multiplying gears and the counter shaft are mounted in the housing 25 to form a compact structure which may be conveniently applied to the brake mast 15. The only
 30 modification of the brake mast or of the usual brake mechanism, which is necessary in order to combine the present invention therewith, is the provision of a square portion 31 at the lower end of the brake mast
 35 and this can be conveniently provided by cutting down the lower extremity of the enlarged portion 15^b upon which the brake chain is ordinarily wound.

Although I have shown and described a
 40 particular embodiment of the invention for purposes of illustration, it will be understood that it may be constructed in various other forms without departing from the scope of the appended claims.

45 I claim:

1. In combination, a brake mast, a housing rotatably mounted with respect to said mast, and compound brake mechanism carried by said housing and connected to said mast.
2. In combination, a brake mast, a housing rotatable freely on said mast, a counter shaft journaled in said housing, and gear mechanism connecting said mast with said counter shaft.
3. In combination, a vertical brake mast, a bearing for the lower end of said mast, a housing supported by said bearing and rotatably engaged by said mast, and compound brake mechanism carried by said housing and operated by said brake mast.
4. In combination, a railway car having an end sill, a brake mast extending vertically past said sill, a step carried by said sill and having said brake mast journaled there-

in, a housing journaled on the lower end of said brake mast, and brake mechanism mounted in said housing and connected to said brake mast.

5. In combination, a railway car having an end sill, a brake mast extending vertically past said sill, a step carried by said sill and having said brake mast journaled therein, a housing journaled on the lower end of said brake mast and supported by said step, and gear mechanism carried by said housing and driven by said brake mast.

6. In combination, a railway car having an end sill, a brake mast extending vertically past said sill, a step carried by said sill and having said brake mast journaled therein, a housing journaled on the lower end of said brake mast and supported by said step, gear mechanism carried by said housing and driven by said brake mast, and ratchet mechanism mounted on said end sill for controlling the rotation of said brake mast.

7. In combination, a brake mast having an enlarged drum portion, a housing rotatably engaged by said drum portion, a counter shaft journaled in said housing parallel to said brake mast, a pinion fixed on said brake mast, a gear fixed on said counter shaft and meshed with said pinion, and a brake chain connected to said counter shaft.

8. In combination, a brake mast, a housing comprising upper and lower arms and a hub portion journaled on said brake mast, said lower arm comprising upper and lower walls forming a chamber, a counter shaft journaled in said upper and lower arms, a pinion mounted in said chamber on said brake mast, a gear mounted on said counter shaft within said chamber, and brake operating means connected to said counter shaft between said upper and lower arms.

9. In combination, an end sill, a brake mast extending vertically past said end sill, supporting means mounted on said brake mast below said sill, a counter shaft journaled in said supporting means, and means for connecting said mast with said counter shaft.

10. In combination, an end sill, a brake mast extending vertically past said end sill, a bracket secured to said end sill and having said brake mast journaled therein, a ratchet wheel mounted on said brake mast adjacent said bracket, a detent mounted on said bracket and adapted to engage said ratchet wheel, a step connected to said end sill and having said brake mast journaled in the lower part thereof, a housing resting on said step and rotatably engaged by said brake mast, a counter shaft carried by said housing, and means connecting said brake mast with said counter shaft.

11. In combination, an end sill, a brake mast extending vertically past said end sill,

a bracket secured to said end sill and having said brake mast journaled therein, a ratchet wheel mounted on said brake mast adjacent said bracket, a detent mounted on said bracket and adapted to engage said ratchet wheel, a housing journaled on the lower end of said brake mast above said step, said housing comprising upper and lower arms, a counter shaft journaled in said arms, gear mechanism connecting said brake mast and 10 said counter shaft within said lower arm, and a brake chain adapted to be wound on said counter shaft between said upper and said lower arms.

In testimony whereof, I have subscribed 15 my name.

EDWARD POSSON.
